BATHYTHERMOGRAPH

Athelstan F. Spilhaus, University Heights, N. Y.,
assignor to Submarine Signal Company, Boston,
Mass., a corporation of Maine

Application December 18, 1941, Serial No. 423,402

6 Claims. (Cl. 73—345)

The present invention relates to bathythermographs and is an improvement upon my previously filed patent application Serial No. 224,074, filed August 10, 1938, and application Serial No. 389,220, filed April 18, 1941.

With respect to the latter application, which relates to a combination of a bathythermograph and sea sampler, the present invention is a continuation-in-part particularly as to elements of construction of the bathythermograph component parts in the application Serial No. 389,220.

In the present construction and also in the construction in the last referred-to application, the pressure-responsive means and the temperature-responsive means are each independently operated and neither one produces any motion of the other means. In this arrangement the pressure-responsive device is assembled at one end of the unit and the temperature-responsive device at the other end of the unit with the pressure-responsive means bearing a recording plate and the temperature-responsive means bearing the arm carrying the stylus marking point.

The arrangement of the apparatus according to the present invention is so made that it might be easily disassembled without having the pressure- and temperature- responsive units interfering with each other. The record produced is that produced on a recording plate which may be provided with a recording surface as, for instance, a surface having a coating of lamp black or the like over which the marking stylus is moved substantially in a flat arc while the recording plate itself may be moved in a direction substantially perpendicular thereto.

Without further discussing the advantages and merits of the present invention it will now be described in the specification below in connection with the drawings illustrating embodiments of the invention in which

Fig. 1 shows the invention in elevation with parts in section;

Fig. 2 shows a section taken on the line 2—2 of Fig. 1;

Fig. 3 shows a section taken on the line 3—3 of Fig. 1;

Fig. 4 shows a section taken on the line 4—4 of Fig. 1;

Fig. 5 shows a modification of the drawing shown in Fig. 1;

Fig. 6 shows a section taken on the line 6—6 of Fig. 5; and

Fig. 7 shows a section taken on the line 7—7 of Fig. 5.

As indicated in Fig. 1, at each end of the bathy-

thermograph there are supporting flanges 1 and 2. Each of these flanges is provided with outwardly extending eyes 3 and 4 which may link to a chain or any other means for lowering the bathythermograph into the water. The flange 1 is provided with two normally extending shoulders, to one 5 of which the cylindrical shell 6 is attached for supporting the Bourdon tube 7 upon which the stylus arm 8 recording mechanism is mounted. This mechanism will be more fully described later. The other flange 2 has an inwardly extending base 9 which is provided with a shoulder portion 10 to which the long cylinder 11 is attached by suitable mounting means. The cylinders 11 and 6 are united together through the collar 12 to which the cylinder 6 is fastened in a shoulder on the outside of the collar by means of screws 13 while on the inside, the collar is joined to the cylinder 11, if desired, permanently through a welded joint. The two end flanges or end supporting members are joined together by means of a series of bars 14, 15, 16 and 17. These bars preferably comprise a channel element 18 in which is inserted a non-metallic solid bar element 19 which may, if desired, be made of non-metallic material, as, for instance, Bakelite or other strong plastic. The bars 14, 15, 16 and 17 so formed are attached by screws 20 and 21, respectively, to projecting shoulders or brackets 22 and 23 respectively projecting from the supporting ends 1 and 2 of the bathythermograph. The bars 18, as indicated in the lower half of Fig. 1, have recessed grooves 24, 24, etc., on the inner side of these bars extending uniformly down the side of the bar as indicated clearly in Fig. 1. These recesses form a support for the helical tube 25 which is in communication with the Bourdon tube 7 and together with the latter serves as the temperature-indicating element. Each turn of the helical tube sets in these grooves in the bars and the tube at the end turn continues upwards in the section 26 passing through a hole 27 in the collar 12 to the Bourdon tube 7 which is supported by the bracket 28 extending from one side of the collar 12, as indicated in Figs. 1 and 2.

The Bourdon indicating element comprises a flat spiral of a couple of turns or more, as desired, spiralling from a center point of the tube on which the stylus arm 8 is mounted having at its end the stylus point 29 which bears against the recording plate 30. The recording plate 30 is removably mounted in a frame 31 recessed to receive the plate 30. The frame 31 is supported from an extending bracket 32 which extends

normally from a plate 33 fastened by means of the screws 34 to the piston 35 movable longitudinally within the cylinder 11 by means of the pressure-responsive element 36. This pressure-responsive element is of the bellows type similar to that described in my previously mentioned application Serial No. 389,220. This bellows type of element is built up in sections. Between each section there is provided an annular flange member 37 having its edge bearing against the cylinder 11 for guiding the bellows longitudinally within the cylindrical tube. The piston 35 is attached to the end-most bellows section. This piston has a rod 38 passing through its center, which rod is surrounded by a helical spring 39 bearing at the upper end against the inside of the piston and at the lower end against an elongated collar 40 resting on the base 9 to which the collar and the bellows are hermetically sealed. The lower end of the rod 38 is extended in an element of smaller section with an end cylindrical element 41 working in a sliding fit within the collar 40. The space between the base surface 42 and the end of the element 41 is the allowable measure of travel of the recording plate 30 so that this distance is made substantially the width of the recording plate 30.

As the pressure increases, the bellows will, of course, tend to be compressed and the piston 35 will be retracted within the cylinder 11, drawing downward the frame 31 and the recording plate 30 carried by it. With an increase in temperature the gas pressure within the helical tube 25 will of course, increase. Since the tube 25 is in communication with the Bourdon tube 7, the spiral of the latter will tend to expand, thereby rotating the stylus arm 8 in an arc and producing a mark by the motion of the stylus point across the recording chart. The recording chart, which may be of glass or some transparent or translucent film, if desired, is inserted in the frame from one side in the same manner as in a projection machine. For this purpose a slot 43 is provided at the side of the frame against which a spring finger 44 may rest to hold the slot in position. A spring finger 45 may also be used on top of the recording plate to hold the plate firmly down in its groove. When it is desired to remove the recording plate 30, the spring finger 44 is drawn out of the slot where it presses against the end of the plate and is rotated on its supporting arm 46 ninety degrees which raises up the stylus arm 8 from the recording plate. This occurs because the stylus arm rests in a cut-away portion 47 in the bar 46 when the point 29 is in contact with the recording plate so that when the arm 46 is rotated, the stylus arm is lifted up from the plate. This permits the recording plate to be removed without it being marked upon by the stylus point 29.

In the device as indicated in the figures just described, the supporting bars 14, 15, 16 and 17 are positioned about the device in such a manner that when the device is rested upon a deck of a vessel, for instance, the helical tube element 25 will not come in contact with the deck surface and in this way these projecting bars, in addition to serving as a support for the construction of the bathythermograph, serve also as a special protection for the helical tube element. If desired, these bars may be further supported by an annular member 49 bearing against the cylinder 11, the annular member 49 supporting the bars 14, 15, 16 and 17 and being held thereto by means of the screws 50.

The operation of the device has already substantially been described in connection with the description of Figs. 1 to 4, inclusive. Substantially the temperature-responsive element will produce a record across the recording chart while the pressure-responsive element moves the recording chart itself in a direction substantially normal to the marking of the temperature stylus. The temperature and pressure means are mounted in independent positions at opposite ends of the bathythermograph in such a manner that free operation of each element is obtainable independently of the other. This principle is even more fully followed through in the arrangement shown in Figs. 5, 6 and 7. In this case, the entire assembly of the temperature-responsive means and that of the pressure-responsive means are each constructed as independent units and may be slid together in the final assembly of the bathythermograph. For this purpose the end support 51 carrying the eye member 3 is provided with a shoulder element 52 carrying the cylinder 53. This cylinder is provided at its other end with a heavy flange 54 which supports within it the annular member 55 which may be held by the screws 56 to the cylinder 53. The annular member 55 supports a plurality of equally spaced triangular bars 57 which are provided with V-shaped sawteeth 58 in the greater portion of the length of the bars along the outer apex of the triangle. These V-shaped bars are held to the ring 55 by means of the screws 59 and are also supported at their other end to the annular member 60 by means of the screws 61. The V-shaped bars, therefore, with the end annular members 55 and 60 form a frame upon which the helical tube member 62 which is in communication with the Bourdon tube 63 is spirally wound. The helical tube member 62 extends from the spirally wound portion along one of the triangular bars 57 through a perforation in the annular element 55 to the flat spiral 63 of the Bourdon tube which is supported in position by the clamp 64 supported to a bracket 65 extending from the annular member 55. The construction of the indicating mechanism secured to the Bourdon tube and the recording plate as well as the rest of the mechanism is substantially the same as that described in Figs. 1 to 4, inclusive. The pressure-responsive member is constructed substantially the same as indicated in Figs. 1 to 4, inclusive.

In the modification in Fig. 5, however, the framework supporting the helical tube is supported on the cylinder 11 within which the pressure bellows are guided. If desired, the annular elements 55 and 60 may be held to the cylinder 11, the element 55 by means of the screws 56 and the element 60 by means of the screws 66.

A protecting frame may be built around the helical tube element 58 comprising a framework of the bars 67 which are supported at both ends to flanges in the end-supporting elements. When it is desired to disassemble the unit in Fig. 5, the outer protecting bar 67 may be removed and then the screws 56 and 66 joining the temperature- and pressure-responsive units together. The units may then be easily disassembled after removing the bar 67 by taking out the screw 68 so that the pressure unit and the temperature-responsive unit may be telescoped apart and completely withdrawn from each other.

Other minor modifications and constructions 75 may be employed, but in the above the preferred

embodiments of the invention have been described.

Having now described my invention, I claim:

1. A bathythermograph comprising an elongated cylindrical casing containing and supporting within it a Bourdon tube having a recording element including a stylus operated thereby, a supporting frame axially aligned with said cylindrical casing and supported thereby, a helical tube in communication with said Bourdon tube wound about said supporting frame and being adapted to produce pressure variations for the operation of said Bourdon tube in response to variations in temperature of said helical tube, and a pressure-responsive bellows element supported at one end of said casing and telescoping in axial relationship therewith, said pressure-responsive bellows carrying at its free end a recording chart adapted to be moved by said pressure-responsive bellows longitudinally of said casing, said stylus being adapted to move substantially in an arc over said recording chart.

2. A bathythermograph comprising an elongated cylinder having a Bourdon tube mounted at one end thereof with a recording stylus carrying arm operated thereby positioned substantially in the longitudinal axis of the cylinder and adapted to rotate about an axis perpendicular thereto, a temperature-responsive helical tube element in communication with said Bourdon tube for operation of the latter, said helical tube being mounted concentrically with said cylinder and outside of the same, a pressure-responsive bellows element positioned longitudinally in said cylinder and supported at one of its ends to the other end of the cylinder, said bellows having at its other, free end a recording plate positioned in the plane of motion of the recording stylus, the expansive and contractive motion of said pressure-responsive bellows being adapted to move said recording plate in an extension of its same plane and the motion of said stylus arm being adapted to move said stylus over the surface of said recording element.

3. A bathythermograph comprising an elongated supporting frame having a Bourdon tube mounted at one end thereof with a recording stylus positioned substantially in the longitudinal axis of the frame and adapted to be rotated about an axis perpendicular thereto by operation of said Bourdon tube, an elongated cylinder concentrically supported in the direction of the longitudinal axis of said frame, a pressure-responsive bellows element within said cylinder adapted to be operated by variations in pressure in the direction of the longitudinal axis of said frame, a recording plate supported at one end of said bellows element, said recording plate being positioned in a plane substantially coextensive with the plane of motion of the recording stylus, said Bourdon tube having in communication therewith a temperature responsive helical tube mounted and supported substantially concentrically with said elongated cylinder.

4. A bathythermograph comprising an elongated supporting frame having a Bourdon tube

mounted at one end thereof with a recording stylus positioned substantially in the longitudinal axis of the frame and adapted to be rotated about an axis perpendicular thereto by operation of said Bourdon tube, an elongated cylinder concentrically supported in the direction of the longitudinal axis of said frame, a pressure-responsive bellows element within said cylinder adapted to be operated by variations in pressure in the direction of the longitudinal axis of said frame, a recording plate supported at one end of said bellows element, said recording plate being positioned in a plane substantially coextensive with the plane of motion of the recording stylus, said Bourdon tube having in communication therewith a temperature responsive helical tube mounted and supported substantially concentrically with said elongated cylinder, said supporting frame surrounding said helical tube and serving as a protection therefor.

5. A bathythermograph comprising an elongated supporting frame having a cylindrical casing extending from one end thereof containing and supporting within it a Bourdon tube, said Bourdon tube having in communication with it a temperature responsive helical tube wound on the supporting frame and coaxially positioned with respect to said cylindrical casing, a pressure-responsive bellows element positioned longitudinally in said frame and supported at one of its ends to the other end of the frame, said bellows having at its other, free end a recording plate positioned in the plane of motion of a recording stylus, said recording stylus being carried by said Bourdon tube, the expansive and contractive motion of said pressure-responsive bellows being adapted to move said recording plate in an extension of its same plane and the motion of said Bourdon tube being adapted to move said stylus over the surface of said recording plate.

6. A bathythermograph comprising an elongated supporting frame having a cylindrical casing extending from one end thereof containing and supporting within it a Bourdon tube, a second frame comprising a plurality of bars extending longitudinally in the direction of said cylindrical casing and forming a framework having a temperature responsive helical tube extending from and in communication with said Bourdon tube and wound and supported on said framework, a pressure-responsive bellows element positioned and with one end thereof at the other end of the first frame, a cylindrical casing coaxial with the axis of said first frame and providing a guide for the longitudinal movement of said bellows element, said cylinder externally supporting the frame on which said helical tube is mounted, said pressure-responsive bellows carrying at its free end a recording chart adapted to be moved with said pressure-responsive bellows longitudinally of said frame and a stylus carried by said Bourdon tube and being adapted to move over said recording plate substantially in an arc.

ATHELSTAN F. SPILHAUS.
